poration of Delaware

Application November 5, 1937, Serial No. 173,030

7 Claims. (Cl. 257—245)

This invention relates to heat exchangers of the separable plate type, and particularly to means for sealing the joints between adjacent plates. These joints, generally stated, are of two types, i. e., joints around the marginal periphery of the plates and joints around the margins of flow ports formed through the plates. Depending on the design of the plate and the particular use for which the plate is used in a given heat exchanger, the flow ports may be within the marginal joint or outside the marginal joint, and in certain types of plate one or more ports may be within the marginal joint and another port or ports may be outside the marginal joint. The present invention permits satisfactory seals to be produced irrespective of the location of the through port with reference to the marginal joint.

For many years the advantage of forming the plates of thin sheet metal pressed to produce flow controlling ribs or bosses has been recognized. The present invention is particularly adapted for use with plates of this type, but is capable of use with other types. In recent years, commercial heat exchangers have been constructed, making use of pressed plates formed of non-corrosive alloy steels, and the advantage of such steels, particularly in dairy apparatus, is too well known to require elaboration. For example, the patent to Seligman, 1,992,097, February 19, 1935, shows a plate of this general character having flat marginal portions in which the through ports are formed and with which the necessary seals are produced by gasket-carrying spacers interposed between successive plates. These spacers, as shown in the Seligman patent, comprise a frame which is grooved on opposite faces to receive rubber gaskets, the gaskets being cemented or vulcanized in place in these grooves. The only disadvantage of this construction is the possibility that if the gaskets do not completely fill the grooves, or if the gaskets are not closely cemented or vulcanized in place, small fissures in which bacteria may breed are afforded. Even if the gasket carrier is initially perfect, it may, after long use develop fissures between the carrier and gasket.

Another patent to Seligman No. 2,075,236, March 30, 1937, eliminates the gasket carriers as separate elements and provides grooves formed at least in part by pressing the plate, in which grooves the gaskets are cemented or vulcanized. This construction, while simpler than that shown in the earlier Seligman patent, is open to the same possible objection.

The present invention resembles the structure of the earlier Seligman patent to the extent that a separate carrier element is used, but it differs from that Seligman patent in that the carrier is a thin plate and in that the gasket is not mounted in a face groove but, on the contrary, it is U-shaped in cross section and embraces the edge of a suitable opening formed in the carrier plate in such a way that the edges of the slot between the arms of the U-section of the gasket are presented to the exterior of the heat exchanger, and consequently even if a fissure between gasket and carrier plate be present, initially or after use, it is wholly external to the path of fluid undergoing treatment, and hence 15 harmless.

Another distinction from the earlier Seligman patent above mentioned is that the marginal portions of the plate, instead of being flat, are offset in such a way as to offer a shoulder or abutment against which the inner margin of the gasket ring seats. Consequently, when the plates are forced together and the gasket rings, which are customarily made of rubber or the like, are compressed, their lateral expansion is resisted and limited by the shoulder on the plate. Since the shoulder limits inward displacement, and the gasket carrier plate resists outward displacement, undue distortion or spreading of the gasket is prevented. Hence the gasket is no more severely deformed than it would be if confined in a groove. Another important fact is that the area of the gasket exposed to fluid pressure is small so that the total force tending to blow the gasket out is comparatively small. It follows from the facts above set forth that the joint is sanitary and the gasket is adequately sustained against pressure and is forced to perform in such a way that the formation of internal fissures, even of a temporary character, is minimized if not entirely eliminated.

It may be asked why it is necessary in the structure of the two Seligman patents to cement or vulcanize the gaskets in place. The reason is that the plates are customarily used in the vertical position and are not removed from the press for cleaning but are cleaned in such vertical position. Some means must be provided for holding the relatively flexible gaskets in place. Further, with the temperatures customarily used, the gaskets if made of rubber, as is the present practice in such heat exchangers, would have a tendency ultimately to lose their precise form and dimensions unless they were adequately sustained.

The invention will now be described with reference to typical plates used in heat exchangers of this type. Where heating and cooling are carried out in a single exchanger, and particularly where there is regenerative heating and cooling as is common in this art, the plates for a single interchanger assume various forms. There are commonly end plates, right hand plates, left hand plates, etc., which differ from each other chiefly in the location of the ports or in the presence or absence of certain ports. These facts are well understood. Generally stated, the gasket plates conform to the heat transfer plates with which they are intended to be used.

For present purposes it is deemed sufficient to illustrate typical heat exchange plates and typical gasket plates for use therewith. Except as to cooperation with the gasket, the particular form of plate is immaterial. Consequently, it should be understood clearly that no effort is here made to illustrate every possible form of gasket plate which might be used with the various known forms of heat exchange plate. The illustration and description here given are to be considered exemplary and not limiting. Gasket plates embodying the invention can be designed to meet every requirement of this type of exchanger by simply conforming the gasket plate to the heat exchange plate with which it is intended to be used, according to principles illustrated by the examples chosen for explanation.

In the drawings—

Fig. 1 is a face view of what is called a left hand heat transfer plate. In the present specification the "face" of the plate will be defined as the raised or embossed side and the recessed or intaglio side will be called the "back". The face view of a right hand plate is merely a mirror view of Fig. 1, that is, the parts shown in Fig. 1 on the left will be on the right in the right hand plate, and vice versa.

Fig. 2 is a view of a gasket plate capable of use with all types of left hand plates shown in Fig. 1 and all types of right hand plates of the same design. In Fig. 2 it is shown in position to overlie the left hand plate of Fig. 1. For use with a right hand plate the gasket plate would be turned front to back, so that the upper annular port gasket would be to the right, and the lower annular port gasket would be to the left instead of in the positions shown in Fig. 2.

Fig. 3 is a perspective view of the left hand plate of Fig. 1, with the gasket plate of Fig. 2 in position. Only the lower ends of the two plates are shown and the parts are broken away so as to show the construction and particularly to show how the gaskets on the gasket plate seat against the flange and the shoulder of the heat transfer plate.

Fig. 4 is a face view of what is called an end plate. This plate is ordinarily used as one terminal plate of a series and differs from the left hand and right hand plates in the fact that the space in its face does not communicate with any port.

Fig. 5 is a face view of a gasket plate for use with end plates such as that shown in Fig. 4. Fig. 5 is drawn on a slightly larger scale than Fig. 4.

Fig. 6 is a fragmentary sectional view through the margins of three adjacent plates with two interposed gasket plates. The first and second plates (counting downward) are shown separated so that the gasket is not under compression. The second and third plates are shown positioned as they would be under compression, the purpose of

the view being to indicate the position and configuration of the gasket when performing its sealing function.

Fig. 7 is a sectional view drawn on a somewhat larger scale than the other views, showing an end plate, a left hand plate, a right hand plate, a left hand plate and a right hand plate, assembled in the order stated from right to left, between two clamping heads and with the necessary gasket plates. The gasket plates at the opposite ends of the series are of the type shown in Fig. 5. The others are of the type shown in Fig. 2. The line of section is indicated at 7—7 on Fig. 5.

Fig. 8 is a fragmentary view similar to the lower portion of Fig. 6 but showing a possible modification omitting the gasket shoulder on the heat transfer plates.

Figs. 9 and 10 show modified gasket plate constructions.

Before attempting a detailed description, it might be helpful to point out that with heat exchangers of the type shown in the Seligman patents, the assembled plates are so formed as to afford intervening spaces. Assuming for convenience in discussion, that the liquid to be treated is milk, the space between the first and second plates would afford a passage for heat transfer medium such as heated water or refrigerated water. The space between the second and third plates would afford a passage for milk and that between the third and fourth for heat transfer medium, and so on in alternation through the series. An elaboration of the idea involving what is called regenerative heating and cooling would involve heat transfer between warm milk and cold milk flowing in alternate intervals between plates. For example, when used in conjunction with a pasteurizer, warm milk entering the exchanger from the pasteurizer might exchange heat with cold milk flowing to the pasteurizer through the exchanger.

The flow ducts through which the milk and heat exchange fluid approach and leave the heat exchange spaces are formed by registering the openings in the stack of plates. These must communicate with the proper heat exchange spaces and this result is produced, as it is in the Seligman patents, by causing the gasket which encloses the heat exchange spaces between any two successive plates, either to embrace or to exclude the flow passage, depending on whether there is or is not to be communication between the heat exchange plate and that particular passage.

Generally stated, there are usually four passages in each plate, i. e., an entrance passage in each plate for heat exchange liquid and an exit for heat exchange liquid, an entrance passage for milk and an exit passage for milk. Only two of these can communicate with any particular heat exchange space.

However, it should be remembered that according to the treatment desired, the milk may flow through several heat exchange passages in series, or it may flow through said passages in parallel, and the same is true of the heat exchange liquid. Consequently, referring to the left hand plate, Fig. 1 (and the same is true of its counterpart, the right hand plate), various port arrangements may be necessary. For example, the normal plate has four ports, but under certain circumstances, where the plate is the terminal plate for feeding flow, there may be no ports. Certain other plates will have only three ports, two ports or one port, according to require- 75

ments of circulation. There are four possible arrangements of three ports. There are also four possible arrangements in which there is only one port and six possible arrangements of two ports. Thus, for a left hand plate there are sixteen possible port arrangements. Similarly there are sixteen port arrangements for a right hand plate. The same thing is true of the end plate, but for practical purposes only a few of the possible port arrangements are used. It is not deemed necessary to elaborate.

In the practical manufacture of the plates, as proposed in Figs. 1 to 7 inclusive, the manufacturing process is to strike up the boss forming the shoulder around the port and then to cut the ports within the margin of this boss where ports are desired. Whether the boss has a port in it or not, it requires a gasket, and the gasket seals in exactly the same way whether the boss is ported or not. Since the present invention relates chiefly to the gasket structure and its coordination with the plate, it is unnecessary to elaborate the port arrangement because the location of the gaskets is the same whether the boss is ported or blank.

All the plates, whether of the heat exchange, the end, or the gasket type, may, if desired, have similar external outlines, and are so shown. The plates have at their upper ends a perforated ear 11 and at their lower ends a slotted ear 12, this being chosen as a convenient supporting and alining means. The perforations in ears 11 receive the plate supporting rod 13 (Fig. 7) and the slotted ears 12 straddle a lower alining rod (not shown) to keep the plates in alinement. This is a known construction. Others may be substituted.

Referring now to the left hand plate 20L, Fig. 1, the plate is pressed from a sheet of stainless steel of uniform thickness and has a flat marginal portion 14 which surrounds the entire plate, and a central raised area 15 formed by embossing the central portion of the plate. The margin of the area 15 takes the form of a shoulder or offset 16. In the area 15 are pressed flow directing means here shown as cross ribs or corrugations 17 intended to ensure sinuous turbulent flow of liquid across the plate. These cross ribs are illustrative merely as one possible flow directing means. Other forms may be substituted, the invention imposing no limitations in this respect. In the construction shown, each wave or corrugation carries at its crest two reversely extending dimples 18 and 19, intended to engage reversely arranged similar dimples on alternating plates and thus sustain the middles of the plates against displacement by fluid pressure differentials.

The plate 20L is illustrated as having four through ports 21, 22, 23, 24. The ports 21 and 22 are surrounded by independent upwardly embossed rims 25 and 26, while the ports 23 and 24 are surrounded by embossed rims 27, 28, which are not independent but are related to or form continuations of shoulder 16. As explained, one or more of the ports 21-24 may be omitted, but regardless of this the rims 25-28 are present.

Between ports 23 and 24 on the one hand and raised area 15 on the other hand are depressions 29, 31, which serve to connect ports 23, 24 with the interplate space on the face side of the plate. Filler pieces 32, 33 (see Fig. 3) are welded into the grooves on the back of the plates, such grooves being incidental to the rearward embossing of depressions. The grooves must be filled

to give a flat continuous sealing area for that gasket which seals against the back of the plate. Spacing dimples 34, 35 are struck up in the depressions 29, 31.

The ports 21, 22, 23 and 24 are not cut until after the plate is embossed. Thus it is easily possible to form plates 20L with no ports, or with 1 port (four combinations) 2 ports (six combinations), 3 ports (four combinations), as well as four ports as shown (total 16 ported left hand plates). While the plate having four ports is the one commonly used the other arrangements are used in certain cases.

The right hand plates 20R (Fig. 7) are merely right to left counterparts (mirror reversals) of the plate 20L, Fig. 1. Right and left plates alternate in a stack and the reversal of dimples 18, 19, ensures that the convex sides of the dimples in one plate oppose the convex sides of the dimples in both of its neighbors, to limit deflection (see Fig. 7).

The end plates 40 of Fig. 4 are similar except the ports in the plate are differently arranged. There is a flat marginal portion 44 surrounding the entire plate, a central raised area 45 surrounded by shoulder 46. There are ribs or corrugations 47 with dimples 48 and 49 reversely arranged with respect to the dimples 18 and 19 of the left hand plate 20L. This last arrangement is chosen arbitrarily and merely entails the result that a left hand plate should adjoin an end plate to secure engagement of the dimples. There are through ports 51, 52, 53, 54, each surrounded by an independent embossed rim 55, 56, 57, 58. As in the case of the plates 20L, 20R, there may be fewer than four ports, but the embossed rims are present in any case to coact with the gaskets.

A gasket plate 60 for use in the face of left hand plates 20L and right hand plates 20R (irrespective of the number of ports in such plates) is shown in Fig. 2. This has a main opening surrounded by gasket 61 and two port openings surrounded by gaskets 62 and 63. As used with plate 20L (Fig. 1) all gaskets would seal against the peripheral portions 14 of the two plates between which it is interposed. Gasket 61 would hug shoulder 16 and the continuing portions of rims 27 and 28 (compare Figs. 1 and 2). Gasket 62 would hug rim 25, and gasket 63 rim 26.

The gaskets are ovoid in cross section and slotted on their outer peripheries at 64 to receive the margins of the openings in plate 60, which they embrace and to which they are cemented or vulcanized. Consideration of Fig. 6 will indicate that the metal to rubber joint between the gasket and its gasket plate is outside the flow path in all cases and that when the gasket is under pressure the gasket is closely confined, is exposed to fluid pressure on only a small area and is sustained in nearly all directions. The compression to which it is subjected tends to close rather than open or produce cracks, and consequently, the difficulties inherent in gaskets mounted in face grooves are avoided. Another advantage is that, since the gasket even in its compressed state (see the lower two plates Fig. 6, also the seals visible in Fig. 7) is much thicker than the plate, any leakage past any gasket will drain outside the machine and no leakage grooves such as have heretofore been cut in the exchange plates are necessary. There is a drainage space between gaskets 61 and 62 and also between 61 and 63 (Fig. 2), between 66 and 67 to 70 (Fig. 5) all very clearly shown in Fig. 7.

The end gasket plate 65 (Fig. 5) has a central opening embraced by main gasket 66 and four through ports embraced by gaskets 67, 68, 69, 70, each formed and mounted as already described.

5 A consideration of Figs. 4 and 5 will make it clear that end gasket plates 65 will seat on the face of end plates 40 and will seal with the back of any plate, particularly left hand plates 20L, and right hand plates 20R.

10 In Fig. 7 the ported heads 11 and 12 typify the usual clamping heads to which the flow connections for the heat exchanging fluids are made in the usual manner. Observe that the end plate 40 and the adjacent left hand plate 20L are 15 shown with blank or unported bosses in the plane of section.

While plates having shoulders 16, 46, and rims 25, 26, 27, 28, 55, 56, 57, 58 are preferred, gasket plates as shown in Figs. 2 and 5 can be used with 20 flat marginal or unshouldered plates of the type (for example) shown in Figs. 3 and 4 of Seligman Patent 1,992,097. This possibility is illustrated in Fig. 8 where 80, 81 represent two successive stacked Seligman plates and 60a represents 25 applicant's gasket plate with gasket 61a. The gasket 61a is not so well confined, as in the preferred construction, and because of the greater area of the gasket exposed to internal fluid pressure, is subject to a greater risk of blowing out 30 if high pressures are used, but the joint between the gasket and its gasket plate is outside the flow path of material flowing through the heat exchanger so that this desirable feature is present.

While rubber is mentioned as the material for 35 the gaskets and noncorrosive steel as the material for the plates, this is suggestive. Any suitable gasket material may be used. Considerable resilience is desirable, as well as resistance to chemical action. For the heat exchange plates, good 40 heat conductivity, surface resistance to corrosion and other chemical action, mechanical strength, and workability are important characteristics. The gasket plates being outside the flow paths may be made of any suitable material, but non- 45 corrosive steel is contemplated as desirable.

50 Material for the gasket plates should have the necessary mechanical strength; and surface resistance to corrosion or other chemical action is desirable but not so important as in the case of heat transfer plates. Because of the simple form, workability is less important than in the case of the highly embossed gasket plates. Thus 55 the gasket plate material and the gasket material may be coordinated, in any commercially desirable way, to offer suitably formed bead gaskets with an external sustaining plate with which the gasket is more or less permanently connected. The important thing is that the gasket shall offer a smooth unbroken surface in the 60 area exposed to flow paths of fluid within the exchanger.

Fig. 9 shows a modified construction of gasket plate in which the plate 60b is completely enclosed in rubber. The gasket bead 61b is extended as a thin covering which surrounds the plate 60b as shown, that plate being otherwise substantially as shown in Figs. 2, 3, 5, 6, 7 and 8.

Fig. 10 shows another construction of gasket plate which may be used at least where temperatures are not too high. Here the gasket bead 61c and the plate 60c are integrally formed but have different physical characteristics. Assuming rubber as the material, bead 61c is of soft vulcanized rubber and plate 60c is hard vulcanized, i. e., is what is sometimes called hard rub-

ber or vulcanite. Such differentiations are familiar to persons skilled in the rubber art.

An important distinction from the structure of Seligman No. 1,992,097, is that the same gasket seals with both plates between which it is interleaved. This applies to the various alternative forms of gasket herein suggested.

While several modifications have been suggested, others are possible within the scope of this invention and the specific disclosures herein made are intended to be illustrative and not limiting.

What is claimed is:

1. In heat exchange apparatus of the separable plate type, the combination of a series of heat exchange plates arranged in spaced stacked relation to form interplate flow channels, at least some of said plates having through ports, some of which ports are adapted to communicate with said interplate channels; gasket plates interleaved between the heat exchange plates and having an opening conforming to said interplate channels and said communicating ports, and at least one port adapted to register with another port in the heat exchange plates; gaskets carried by said gasket plates and surrounding said opening and ports, each such gasket sealing with the two heat exchange plates between which the gasket plate is interleaved and the plates being formed with shoulders conforming to the internal contour of the gaskets, and serving to limit inward displacement of the gaskets, under sealing pressure, whereby flow of the gaskets and the gasket area exposed to fluid pressure are minimized; and clamping means between which said plates are confined under seal producing pressure.

2. A gasket plate for heat exchange apparatus of the plate type, comprising a plate having at least one opening therein; and a resilient gasket embracing and enclosing the wall of said opening and permanently secured thereto to present an unbroken surface within said opening and sealing surfaces at opposite faces of the plate, said opposed sealing surfaces being of small transverse dimension as compared with adjacent portions of the plate, which plate extends from an inner margin between said sealing surfaces outward beyond said sealing surfaces, whereby the plate serves as a relatively deep and rigid member resisting outward displacement of the gasket.

3. A plate type heat exchanger comprising a plurality of generally rectangular heat exchange plates in assembled relation to form a plurality of separate liquid flow channels; and a gasket plate interposed between each two heat exchange plates and having a generally rectangular sealing gasket means permanently secured thereto and having its union with the gasket plate completely external to the path of liquid flow in said channels, the plate extending beyond the gasket sufficiently to serve as a rigid beam resisting outward displacement of the gasket.

4. A sealing gasket plate for plate type heat exchangers, comprising a metal plate having at least one fluid flow opening therein; and a continuous gasket channeled in cross section, and secured to the edge of said opening in such manner that the joint between the gasket and the metal is remote from said flow opening and an unbroken gasket surface is presented thereto, the plate extending from the bottom of the channel in the gasket a substantial distance beyond the gasket, whereby a gasket of moderate sealing area

is adequately sustained against outward displacement by the plate.

5. A sealing gasket plate for interposition between the heat exchange plates of plate type heat exchangers, and comprising a metal plate having a polygonal fluid flow opening therein; and a channeled sealing gasket adapted to seal with the plates between which it is interposed, said gasket surrounding said opening with the marginal portion of said opening in said channel and the joint between said channel and the edge of the plate around the opening facing away from the consequently isolated from contact with fluid flowing through the said opening by the seals formed between the gasket and the adjacent heat exchange plates, a portion of the plate thinner than the gasket even when compressed, extending outward beyond the gasket and serving to sustain the gasket and resist its distortion while affording a drainage path for leakage.

6. In a heat exchanger of the separable plate type, the combination of a series of heat exchange plates arranged in spaced stacked relation to form interplate flow channels, at least some of said plates having through ports some of which ports are adapted to communicate with said interplate channels, said plates being offset to form continuous shoulders one of which surrounds an interplate flow channel and another of which surrounds a port in the plate; apertured gasket plates interleaved between successive exchange

plates, the apertures in said gasket plates conforming to but being larger than the areas embraced by the shoulders on the heat exchange plates whereby the gasket plates are received between the offset portions of the heat exchange plates; continuous gaskets mounted on and enveloping the margins of the apertures in each of said gasket plates and sealing with offset portions of the two adjacent heat exchange plates and with the shoulder on one of said plates, the gasket plates having sufficient width outside the gaskets to sustain the gaskets against outward displacement and the shoulders on the heat exchange plates serving to sustain the gaskets against inward displacement and to limit the area of the gaskets subjected to fluid pressure; and clamping means between which said plates are confined under seal producing pressure.

7. A gasket plate for heat exchangers of the separable plate type comprising a substantially rigid plate having an opening therethrough, and a resilient gasket on the margin of said opening and permanently attached to said plate, said gasket presenting a continuous unbroken surface within the opening and sealing areas projecting above both faces of said plate and each surrounding said opening, and the plate having a portion external to the gasket and adapted to serve as a stiffening member which sustains the gasket against outward displacement.

KEITH P. GROAT.

CERTIFICATE OF CORRECTION.

Patent No. 2,181,250.

November 28, 1939.

KEITH P. GROAT.

It is hereby certified that error appears in the printed specification of the above numbered patent requiring correction as follows: Page 5, first column, line 12, claim 5, for the words "from the" read from and; and that the said Letters Patent should be read with this correction therein that the same may conform to the record of the case in the Patent Office.

Signed and sealed this 26th day of December, A. D. 1939.

(Seal)

Henry Van Arsdale,
Acting Commissioner of Patents.
